TUFTED FABRIC

Joseph K. McCutchen, Ellijay, Ga.

Application November 29, 1957, Serial No. 48,710

Term of patent 3½ years

(Cl. D92—1)

Fig. 1.

Fig. 2.

Fig. 3.

Fig. 4.

Fig. 5.

Fig. 6.

Figure 1 is a plan view of a tufted fabric embodying my design.

Figure 2 is a plan diagrammatic view of the fabric shown in Figure 1, the tufts in Figure 2 being stippled to show contrasting shades.

Figure 3 is a longitudinal section taken on line 3—3 of Figure 2.

Figure 4 is a similar view taken on line 4—4 of Figure 2.

Figure 5 is a similar view taken on line 5—5 of Figure 2.

Figure 6 is a transverse section taken on line 6—6 of Figure 2.

The design comprises relatively wide bands of tufts and the bands have narrow spaces between them. Each band comprises an inner row of relatively large tufts and outer rows of relatively small tufts. The tufts in

each row are longitudinally spaced. Each relatively large tuft is arranged generally centrally of a group of four relatively small tufts, and the group of relatively small tufts is generally square. This application is a continuation-in-part of my application for chenille fabric, filed Jan. 30, 1957, Serial Number D-44,674. Application Serial Number D-44,674, was abandoned March 16, 1958.

I claim:

The ornamental design for a tufted fabric, as shown and described.
